UNITED STATES PATENT OFFICE.

JOSEPH M. BARRETT, OF FOSTORIA, OHIO.

CHAIN-LUBRICATING DEVICE.

1,042,996.

Specification of Letters Patent. Patented Oct. 29, 1912.

Application filed January 26, 1911. Serial No. 604,922.

To all whom it may concern:

Be it known that I, JOSEPH M. BARRETT, a citizen of the United States, residing at Fostoria, in the county of Seneca and State of Ohio, have invented certain new and useful Improvements in Chain-Lubricating Devices, of which the following is a specification.

My invention relates to improvements in chain lubricating devices and comprises especially a device that will lubricate a chain automatically after it is thrown into action, and which will lubricate the pin, the roller, and the bushing simultaneously.

It consists further in the provision of means for regulating the quantity of lubricant discharged into the chain at one time, and further provides means for maintaining the lubricating device always in proper position for engagement with the chain.

It consists further in a lubricating device which is adapted to be actuated and set in operation by the movement of the chain itself, and this takes place regardless of the speed or pitch of the chain.

In the construction shown in the drawings and described herein, which is a preferable embodiment of my idea, it consists primarily of a supporting member provided with radial arms having ducts therethrough adapted to register with the duct in the chain pin and also with the duct communicating with the lubricant reservoir, and as the chain moves, these arms are swung by engagement therewith, so that as each arm is discharging the lubricant into the chain, it is being swung, and the succeeding arm is being positioned for engagement with the succeeding chain pin. The engagement of the chain pin with the arm will cause the supporting member upon which the arms are mounted to be moved away from the chain, and this movement is accommodated by providing a slideway therefor, and resilient means for returning the same to its proper position.

It consists in further parts and their combinations, all of which will be specifically hereinafter described and set forth in the claims.

Referring to the drawings which are hereto attached and hereby made a part of this

specification, Figure 1 is a plan view of my improved lubricating device and a portion of the chain, showing the manner of engagement with the chain; Fig. 2 is a vertical longitudinal section along the line 1—2 of Fig. 1.

In the drawings in which the same numeral indicates the same part throughout, K is a base plate provided with the tongue K', the base plate as here shown having a yoke shape; secured to the arms of the yoke adjacent to its open end is a bar L secured in place by bolts L'. Mounted to slide upon the tongue K' on the base plate K is a supporting member D, which is adapted to reciprocate upon the plate K; mounted upon the rear portion of the plate K is a member K² having a projection R thereon, and from the supporting member D extends the projection R'; these projections are arranged to receive the coiled spring J, and on account of the space between the free ends of the projections, the supporting member D is capable of the reciprocating movement above mentioned. When the supporting member D has been moved against the resistance of the spring J hereafter to be described, the resiliency of the spring will cause the same to be moved forward again and to assume its normal position. The purpose of this movement will hereafter be set forth.

The supporting member D has a reduced bearing portion D' thereon, upon which is mounted the collar C. This collar is provided at intervals with openings into which are screwed the radial arms B, there being four such arms shown in the drawings; at the outer end each arm B is formed with a circular enlargement B' having the stem B² formed thereon. The enlargement B' is adapted to be received by a socket formed of the two members A and F secured together by the cap screws S; the socket member F has the extension F' formed thereon with the depending portion F², and the spring G is provided to engage the extension F² and the stem B², to restore them to their proper relative positions. The socket member A has a cup shaped recess A' formed thereon and in this recess there is formed a nozzle or nipple A², preferably integral with

the socket member A. Through the socket member A, the arm B and the bearing portion D' of the supporting member D, are formed the ducts I, which are adapted to register and form a continuous passageway therethrough when desired; a collar member E having the cylindrical extension E' formed thereon, has also formed thereon the cone shaped receptacle E²; a lubricant reservoir O is mounted upon the upper end of the cone E², and is provided with the cap O². It is seen that the cylindrical portion E' is hollowed to form a continuation of the duct I therethrough, communicating with the lubricant reservoir through passageway I', when the plunger H is so positioned as to admit of such communication.

In the lubricant reservoir is mounted the plunger plate Y upon the rod Y', the latter having the threaded portion U at its upper end, and carrying the spring T compressed between the cap O² and the plunger plate Y; the position of the plunger plate in the reservoir is regulated by manipulating the handle N to operate the traveling nut N'.

The plunger H has the stem H' mounted upon the member K² of the base plate K, the stem H' being slotted as shown at H², to receive the pin M, which is threaded at its upper end and carries the nut M'; the position of the plunger H may be changed as desired by loosening the nut M' and sliding the plunger H upon the pin M to any point along the slotted portion H² desired. The collar member E is secured to the bearing member D' adjacent its upper end by the set screws E³.

A portion of the chain is shown in plan in Fig. 1, and in section in Fig. 2, in which X indicates one pair of side bars of the chain, X' indicates another pair, joined by the pin X² upon which is provided the bushing X³, forming a bearing for the roller X⁴; the pin as shown particularly in Fig. 2 is provided with a duct therethrough, having the branch ducts, all being designated by the letter I, leading to the bearing surface between the bushing and the pin and between the roller and bushing. The chain is adapted to be held against lateral displacement adjacent the lubricating device, in any preferred manner, no arrangement for that purpose being herein shown. The head X⁵ of the pin is recessed, as shown, to receive the nipple A² on the socket member A, hereinbefore described, and when the parts are in the position shown in Fig. 2, the ducts I register and form a continuous passageway, as seen. The ducts in the radial arms B are adapted to register with the duct passing through the bearing portion D' of the supporting member and the cylindrical portion E', only after the socket member A has been engaged by the pin head X⁵; this engagement causes the supporting member to be moved away

from the chain, which operation causes the lubricant to pass out into the chain pin. This registration of the duct through the arm B with the duct leading to the reservoir will be maintained only so long as this engagement with the chain pin continues, as it will be seen that it begins before the arm reaches the position shown in the drawing and terminates after the arm has been moved past the position shown in the drawings. It will be understood that the collar member is perforated only at the proper points to permit registration between the duct passing through the arms and the duct leading to the reservoir, and consequently the lubricant can not pass out of the duct leading through the reduced bearing portion D' until an arm has been properly positioned to effect registration of the ducts. This construction renders it impossible for the lubricant to be discharged at any time except when the parts are properly positioned for discharge into the chain pin.

The device is set for operation by placing it close enough to the moving chain, so that the face of the depression A' is farther away from the approaching pin on the chain, engaged by the head X⁵ of the pin, it being understood that the chain is not movable laterally at this point; the effect of the engagement of the head X⁵ of the moving pin is to swivel the socket A upon the bearing B', thereby bringing the nipple into the recess formed in the end of the pin, as shown in Fig. 2, whereupon the head of the pin is embraced by the depression formed in the socket member A. The travel of the chain being in a straight line, the effect of the engagement between the head of the pin and the socket member A, is further to slide the supporting member D, by transmitting the force through the arm B, away from the chain, and this movement of the supporting member D operates to slide the cylinder E upon the plunger H. Before the chain pin engages the socket member A, the lubricating device is so positioned that communication exists between the reservoir O and the passageway I through the duct I', and through this passageway the lubricant is forced by the plunger plate Y acted upon by the spring T, into the continuous passageway I, which is filled with the lubricant to the point where it registers with the continuation of the duct through the arms. When the arm is swung into the proper position, as hereinafter described, the sliding movement imparted to the supporting member D by the engagement with the pin, as described, causes the plunger H to force the lubricant into the duct I in the pin, and consequently through the branch ducts therein into the bearings of the roller and the pin. The forward movement of the chain, at the same time that it is sliding the lubricating

device away from the chain, is also causing the arm B to rotate on the bearing D', and when the pin head X' has passed out of engagement with the socket member A, a second arm is left in proper position to be engaged in a similar manner by the recessed head on the succeeding pin. As soon as the engagement between the chain and the socket member A has ceased, the spring J, which has been compressed by the sliding movement of the supporting member D, expands and moves the whole device toward the moving chain, so that the succeeding arm is positioned properly for engagement with the recessed head of the succeeding pin, whereupon the same cycle of operation is repeated. The plunger H may be adjustably positioned as described above, thereby locating it in the cylindrical portion E' to cause a greater or smaller quantity of the lubricant to pass into the chain pin, as desired; it is readily seen that if the plunger H is positioned as shown in Fig. 2, a certain quantity of the lubricant will be directed into the chain pin, whereas, if the plunger should be positioned toward the right, as shown in Fig. 2, a larger quantity of the lubricant would be forced outwardly, whereas if it were positioned toward the left, a smaller quantity would be forced into the chain pin; thus, the plunger may be positioned to force out the quantity of lubricant desired.

The reservoir is filled in any desired manner, and the plunger plate Y is positioned against the top surface of the lubricant, and the spring exerts a constant pressure thereagainst, tending to force the lubricant out into the continuous passageway at all times; it is apparent that the lubricant will be thus forced into the passageway when the device is waiting to be engaged by an approaching pin. As many arms as desired may be provided upon the collar C, the number required being determined by the frequency of the occurrence of the pins. Further, when the socket A is rotated upon the bearing B', B'', the spring G will always operate to return the socket members to their proper positions.

It is seen that I have provided a device which will be actuated by the movement of the chain itself, and which in all respects is automatic; the amount of the lubricant forced into the bearings can be fixed by properly tensioning the spring T and properly positioning the plunger H, and by this means I can also provide for lubricants for different degrees of solidity.

It will be understood that my device is intended primarily for use with a hard or rather solid lubricant. It is simple in its construction, has no parts which are readily put out of order, is easily manipulated, and withal is effective.

I do not desire to confine myself to the

construction shown in the drawings and set out in the description, but desire to claim all modifications and variations of structure to accomplish the purpose, which are within the scope of my invention.

What I claim is:

1. In combination with a moving chain having a chain pin formed with a longitudinal opening therein having radial outlets, a lubricating device comprising a reciprocating support, a lubricant reservoir mounted thereon, a member mounted thereon having a passageway therethrough permitting communication between said reservoir and said opening in said chain pin and adapted to be engaged by said chain pin to move said support away from said chain, means for forcing the lubricant out through said passageway into said chain pin during said movement of said support, and means for returning said support to its normal position.

2. In combination with a moving chain having a chain pin formed with a longitudinal opening therein communicating with the pin bearing, a lubricating device comprising a supporting member, a lubricant reservoir mounted thereon, a member mounted upon said supporting member and having a passageway therethrough communicating with said reservoir and with the interior of said chain pin and adapted to be engaged by said moving chain pin, whereby said lubricating device is moved away from said chain, means for forcing the lubricant into said chain pin during said movement, and means for returning said lubricating device to normal position.

3. In combination with a moving chain having a chain pin formed with a longitudinal opening therein communicating with the bearing of said pin, a lubricating device comprising a supporting member mounted for reciprocation, a lubricant reservoir carried thereon, a member mounted upon said supporting member and having a passageway therethrough communicating with said reservoir and with the interior of said chain pin and adapted to be engaged by said chain pin whereby said lubricating device is given a movement away from said chain, a plunger member positioned to force the lubricant through said passageway into said chain pin during said movement of the lubricating device, and means for returning the lubricating device to its normal position.

4. In combination with a moving chain having a chain pin formed with a longitudinal opening therein communicating with the bearing of said pin, a lubricating device comprising a supporting member mounted for reciprocation, a reservoir carried thereon, a member mounted upon said supporting member and having a passageway therethrough communicating with said reservoir

- and with the interior of said chain pin and adapted to be engaged by said chain pin, whereby the lubricating device is given a movement away from said chain, an adjustable plunger member positioned to force the lubricant through said passageway into said chain pin during said movement of the lubricating device, and means for returning the lubricating device to its normal position.
- 10 5. A chain lubricating device comprising a central supporting member having a passageway therethrough mounted for reciprocation and adapted to be moved in one direction by engagement with a moving chain, means for moving said central supporting member in the opposite direction, hollow arms mounted radially on said central supporting member, a lubricant reservoir mounted on said supporting member and having communication through said passageway with said hollow arms, and means for forcing the lubricant into the chain during the reciprocating movement of said central supporting member.
- 15 6. A chain lubricating device comprising a central supporting member mounted for reciprocation and having a passageway therethrough, and adapted to be moved in one direction by engagement with the moving chain, means for moving said supporting member in the opposite direction, hollow arms rotatably mounted upon said supporting member, a lubricant reservoir mounted on said supporting member, there being a continuous duct leading from said reservoir to said hollow arms, the engagement of said chain with said hollow arms effecting the movement of said supporting member, and means provided to force the lubricant out through said duct during the movement of said supporting member on account of the engagement with the chain.
- 20 7. A chain lubricating device comprising a supporting member mounted for reciprocation, a lubricant reservoir, radial arms rotatably mounted upon said supporting member and adapted to be engaged by the chain pin of a moving chain, whereby said arms are given a rotary and a radial movement, means for establishing communication between said reservoir and said chain pin during the engagement of said chain pin and said arm, means for forcing the discharge of the lubricant into the chain pin during said engagement and for determining the quantity of lubricant thus discharged.
- 25 8. A chain lubricating device comprising a supporting member mounted for reciprocation, a lubricant reservoir thereon, radial arms rotatably mounted upon said supporting member and adapted to be engaged by the pin on a moving chain to compel both a rotary and a radial movement thereof, ducts appropriately provided for registration during said engagement whereby communication is established between said reservoir and said chain pin, a plunger member positioned in said duct, whereby during said radial movement of said arms the lubricant is forced into the chain pin, and the quantity of the lubricant thus discharged is determined.
- 30 9. A chain lubricating device comprising a central supporting member mounted for reciprocation, a lubricant reservoir thereon, radial arms rotatably mounted upon said supporting member, a socket member rotatably mounted upon the outer end of each of said arms and adapted to be engaged by the head of a chain pin on a moving chain, whereby said arm is moved both rotatably and radially, ducts adapted for registration through said chain pin, socket member, radial arm, and supporting member, whereby communication may be established between said reservoir and said chain pin, and means appropriately positioned for compelling the discharge of lubricant into the chain pin during the engagement between said chain pin and said socket member, and for determining the quantity of lubricant to be discharged.
- 35 10. A chain lubricating device comprising a supporting member mounted for reciprocation, a lubricant reservoir thereon, means for applying pressure to the lubricant in said reservoir for forcing the same outwardly therefrom, hollow radial arms rotatably mounted upon said supporting member and adapted to receive the lubricant from said reservoir during a predetermined portion of their rotary movement, a socket member flexibly mounted upon the end of said arm for engagement with the pin of a moving chain, said pin being provided with a passageway thereinto communicating with its bearings at one end and the passageway leading to said reservoir at its other end, the engagement between said pin and said socket member being adapted to produce a rotary movement of said arm, whereby a continuous communication is established between said reservoir and said chain pin, and further adapted to produce a radial movement of said arm whereby the lubricant is discharged into said chain pin, and means for determining the quantity of lubricant thus discharged.
- 40 11. A chain lubricating device comprising a central supporting member mounted for reciprocation, a lubricant reservoir thereon, radial arms rotatably mounted upon said supporting member and constructed to have communication therethrough with said reservoir, a moving chain having hollowed chain pins provided with heads adapted to engage a radial arm whereby said arm is given both a radial and a rotary movement, whereby said chain pin is lubricated and a

1,042,996

5

- succeeding arm is properly positioned for engagement with the succeeding chain pin.
12. A chain lubricating device comprising a central supporting member mounted for reciprocation, a lubricant reservoir thereon, a plurality of radial arms rotatably mounted upon said supporting member and having a duct therethrough communicating with said reservoir, a plunger member provided appropriately in said communicating passageway, a moving chain having hollow pins provided with heads adapted to engage a radial arm, whereby, through the movement of said chain, said radial arm is rotated and is given a radial movement whereby lubricant is discharged into said chain pin, and a succeeding arm is properly positioned for engagement with the succeeding chain pin.
13. In a device of the kind set forth, the combination of a rotatable head having a plurality of radially extending tubular arms, means for supplying lubricant to the inner ends of said arms, discharge nozzles mounted on the outer ends of the arms and adapted to connect with the lubricant openings of a chain or other similar mechanism, said nozzles being constructed to turn through a limited arc with respect to their supporting

arms on an axis normal to the plane of rotation of the head, and yielding means for holding the nozzles in a definite position with respect to the arms, substantially as set forth.

14. In a device of the class set forth, the combination of a tubular arm for discharging lubricant and adapted to move so that its discharge end can be maintained in engagement with the lubricant openings of a chain or similar mechanism through a limited distance, means for applying lubricant to the receiving end of said arm, a discharge nozzle mounted on the outer end of the arm and adapted to connect with the lubricant openings of a chain or similar mechanism, said nozzle being constructed to turn through a limited arc with respect to the tubular arm on an axis normal to the plane of movement of the arm, and yielding means for holding the nozzle in a definite position with respect to the arm.

In testimony whereof I affix my signature in the presence of two witnesses.

JOSEPH M. BARRETT.
